United States Patent Office

Des. 193,666
Patented Sept. 25, 1962

193,666

FIGURINE

Raymond R. Miner, Milwaukee, Wis., assignor to John Pavlik, West Milwaukee, Wis.

Filed Dec. 15, 1959, Ser. No. 58,669

Term of patent 14 years

(Cl. D29—23)

FIG. 1

FIG. 4

FIG. 2

FIG. 3

FIG. 1 is a front elevational view of a figurine, showing my new design;

FIG. 2 is a perspective right-hand side view;

FIG. 3 is a perspective left-hand side view, and

FIG. 4 is a perspective rear view.

I claim:

The ornamental design for a figurine, substantially as shown.
